UNITED STATES PATENT OFFICE.

LUTHER D. EARL, OF SHELBY, OHIO.

TOOL FOR PIERCING BILLETS.

1,374,369.

Specification of Letters Patent. Patented Apr. 12, 1921.

Application filed March 29, 1919. Serial No. 286,202.

To all whom it may concern:

Be it known that I, LUTHER D. EARL, a citizen of the United States, residing at Shelby, in the county of Richland and State 5 of Ohio, have invented a certain new and useful Improvement in Tools for Piercing Billets, of which the following is a full, clear, and exact description, reference being had to the accompanying drawings.

10 This invention relates to tools for piercing billets and has for its general object to provide such tools with points which will increase the efficiency thereof. More limit- 65 edly the object of the invention is to pro- vide a point having an efficient means for cooling the same; also to provide a point 70 the shape whereof will facilitate and pro- 75 mote the piercing operation. I accomplish the foregoing objects in and through the 80 construction shown in the drawings forming part hereof, wherein Figure 1 represents a 85 sectional view through a portion of a billet- 90 piercing tool, the billet with which it co- 95 operates being shown in elevation; and Fig. 2 an enlarged detail in elevation of a portion of the point of such tool.

Describing the various parts by reference characters, 1 denotes a portion of a billet, which may be formed into a seamless tube, 30 and 2 a hollow bar or shank forming a part of the tool. At its forward or work facing end, it is provided with the point which pierces the billet in the process of forming a tube or other object therefrom. This 35 point comprises generally a body member 3 and a detachable point member, indicated at 4. The rear end of the body member 3 is reduced, as shown at 5, to form a close fit within the front end of the bar or shank 2, 40 to which it may be secured as by a pin 5a. Intermediate of its ends, the member 3 is enlarged, as shown at 6, the front and rear of such enlargement providing shoulders, the rear shoulder, indicated at 7, forming an 45 abutment for the point proper. Extending forwardly from the front shoulder is an externally threaded portion 9; in front of of this threaded portion there is provided an annular channel, and from this channel 10 50 the front portion of the member 3 is tapered or frusto-conical in shape, as shown at 11. Grooves 12 extend longitudinally of the frusto-conical surface, communicating at their rear ends with the channel 10 and at 55 their front ends with a chamber formed within the point member. From the an-

nular channel, ports 13 extend to a central bore 14 provided within the body 3. This bore is contracted at its forward end in order to form a close fit with a tube 15, which 60 extends through the hollow bar or shank 2 and entirely through the bore 14 and the reduced front thereof.

The point member, indicated at 4, is gen- 65 erally tapered from rear to front and is pro- vided at its front end with a rounded knob 4a. The inner wall of the point member is so shaped as to conform to the parts 9 and 11 of the body 3, the rear end of the wall being threaded upon the portion 9 of said 70 body. From this internally threaded por- 75 tion, the inner wall of the point member is tapered or frusto-conical whereby, when screwed home upon the body 3, it forms a tight fit with the exterior surface of the 80 portion 11 thereof. In front of the tapered end of said body, the point member is pro- 85 vided with a chamber 16 into which the front end of the tube 15 projects. In operation, a cooling fluid, such as water, will be sup- 90 plied through the tube 15 into the chamber 16 whence it will flow through the channels provided by the interior of the point mem- 95 ber and the grooves 12 to the annular groove 10 and thence through the ports 13 to the en- 100 larged portion of the bore 14 and through the interior of the hollow bar or shank 2.

By this arrangement of parts, the working end or point of the piercing tool is effectively cooled. Furthermore, the rounded knob 4a 90 facilitates the piercing of the billet and tends to prevent the point from drifting as it passes through the latter.

Having thus described my invention, 95 what I claim is:

1. In a tool of the character described, the combination of a hollow bar or shank, a chambered point at the forward end of said bar or shank, a fluid supply extending to the chamber of said point, and a plurality 100 of passageways in said point communicating with the chamber and conducting fluid therefrom in cooling relation to said point.

2. In a tool of the character described, the combination of a bar or shank, a connecting 105 body at the forward end of said bar or shank, a chambered point detachably mounted on said body, a fluid supply extending through said body and communicating with the chamber of said point, and a plurality 110 of passageways in said body communicating with the chamber and conducting fluid

therefrom in cooling relation to said point and to a discharge outlet therefrom.

3. In a tool of the character described, the combination of a bar or shank, said bar or shank having at its forward end a tapered body, said tapered body being provided with a bore extending therethrough and reduced at its forward end, a tube extending through said bar or shank and said bore and forming a close fit with the contracted forward end thereof, a point carried by said body and having a chamber in front of the same and in front of said tube, and passageways communicating with said chamber and extending rearwardly therefrom and communicating with the enlarged portion of said bore.

4. In a tool of the character described, the combination of a bar or shank, said bar or shank having at its forward end a tapered body, said tapered body being provided with a bore extending therethrough and reduced at its forward end, a tube extending through said bar or shank and said bore and forming a close fit with the contracted forward end thereof, a point detachably connected to said body and forming a close fit with the tapered end thereof and having in front of such tapered end and of said tube a chamber, ports being formed between the inner tapered wall of said point and the outer tapered wall of said body, an annular channel with which the said ports communicate, and ports extending from said channel and communicating with the enlarged portion of said bore.

5. In a tool of the character described, the combination of a bar or shank, a tapered point thereon, the said point having therein a plurality of passageways extending longitudinally thereof and in cooling relation to the outer tapered surface thereof, and connections for circulating fluid through said passageways.

6. In a tool of the character described, the combination of a shank or bar, a tapered point carried thereby, said point having a plurality of passageways therewithin and extending substantially parallel with the outer tapered surface thereof, the said point having a chamber in its front portion with which said passageways communicate, means

for conducting fluid to such chamber, and a plurality of passageways communicating with the rear ends of the first passageways, respectively, and conducting the fluid supplied through the first mentioned passageways to the central portion of the said shank or bar.

7. In a tool of the character described, the combination of a bar or shank, said bar or shank having at its forward end a body provided with an external thread and with a frusto-conical projection in front of such thread, the said body being provided with a bore which is reduced at its forward end, a tube within said bar or shank and fitting closely within the contracted portion of the said bore, a point having an internal thread coöperating with the thread of said body and having a frusto-conical inner wall adapted to contact with the frusto-conical wall of said body and provided with a chamber in front of said body, the said body being provided with a plurality of grooves in the frusto-conical wall thereof and extending longitudinally of such body communicating at their front ends with said chamber and at their rear ends with an annular groove provided in said body at the rear end of the frusto-conical wall thereof, there being ports extending from said groove inwardly to the enlarged portion of said bore.

8. In a tool of the character described, the combination of a bar or shank, said bar or shank having at its forward end a tapered body, said tapered body being provided with a bore extending therethrough, a point detachably connected to said body and forming a close fit with the tapered end thereof and having a chamber in front of such tapered end, ports being formed between the inner tapered wall of said point and the outer tapered wall of said body, and means for circulating a fluid through said bore, chamber and ports.

9. A tool of the character described having a tapered point provided at its forward end with a rounded knob or projection.

In testimony whereof I hereunto affix my signature.

LUTHER D. EARL.
